WALL-MOUNTED HOUSING FOR A SPACE CONDITION RESPONSIVE INSTRUMENT

Billy Burley, Dallas, Tex., assignor, by mesne assignments, to Johnson Service Company, Milwaukee, Wis., a corporation of Wisconsin

Filed June 13, 1962, Ser. No. 70,537

Term of patent 14 years

(Cl. D52—7)

FIG. 1 is a front view of the wall mounted housing for a space condition responsive instrument embodying my new design;

FIGS. 2 and 3 are side views thereof, taken from opposite sides;

FIG. 4 is a top view thereof, and

FIG. 5 is a cross sectional view taken on line 5—5 of FIG. 1.

The essential features of the design reside in the portions shown in full lines. It is to be understood that the perforations on the face of the instrument are repeated throughout the area.

I claim:

The ornamental design for a wall-mounted housing for a space condition responsive instrument, as shown and described.
